BERTRAM G. WORK AND LOUISA N. SLADE, OF NEW YORK, N. Y., ASSIGNEES TO THE
B. F. GOODRICH COMPANY, OF NEW YORK, N. Y., A CORPORATION OF NEW YORK.

REDUCING GARMENT.

Application filed September 18, 1924. Serial No. 737,988.

This invention relates to reducing garments in the form of abdominal girdles, corsets, etc. of an elastic construction obtained by the use of sheet rubber, and its principal object is to provide a garment of this character adapted to fit comfortably on the body while exerting the desired reducing pressure thereon, to control the escape of perspiration and permit its absorption in a fabric cover forming a part of the article, to render such cover removable from the rubber portion or lining so that both parts may be effectively cleansed, and to coordinate the structure and relation of the cover and lining in such a manner as to allow for the expansion of said lining while providing a smooth fitting cover when the garment is in use.

Of the accompanying drawings, Fig. 1 is an elevation showing mainly the front of our improved reducing garment in a preferred form, with one margin of the cover unfastened and turned back.

Fig. 2 is an elevation showing mainly the rear of the garment with the cover and rear stay-pockets partly broken away.

In the drawings, 10 is the lining of the garment made of elastic, vulcanized sheet rubber, and preferably comprising two wide panels 11 adapted to embrace the front, sides and rear of the body, and a narrow rear panel 12 connected with the panels 11 by means of flat, tubular binding strips 13 of fabric cemented and stitched to the margins of the sheet rubber and constituting sheaths or pockets for the stiff, flexible stays 14. The top edge of the lining and the bottom front edges thereof are provided with fabric binding tapes 15, 16 secured in like manner to the sheet rubber, and the vertical front edges are provided with similarly attached, relatively-wide fabric bindings 17, 18, preferably made tubular for the reception of stiff, flexible stays 19 of suitable length. The usual or any suitable corset fastenings and adjustment may be provided, preferably at the front as here shown, the edge of the binding 17 being furnished with a row of loops or eyes 20 engaging with a row of hooks 21 on a vertical hook-strip 22, said strip being adjustably connected with the edge binding 18 by means of a lacing 23.

We provide the sheet rubber lining of our garment with a large number of small perforations 24, indicated in Fig. 1 and partly shown in Fig. 2, for the purpose of per-

mitting a direct escape of perspiration through the lining instead of compelling it to pass entirely around the edges thereof between the lining and the body or along the fabric undergarment over which the reducing girdle is preferably worn. Such control of the escaping perspiration renders the garment more comfortable and sanitary, while permitting it to exercise its supporting and reducing functions, and the perforation of the rubber at the same time renders the lining more stretchable, more completely conformable, and more comfortable to the wearer than an imperforate lining. The perforation of the rubber panels is preferably accomplished by punching minute disks out of said panels after the latter have been vulcanized, but the foraminous construction may be obtained in any other suitable way.

25 is a fabric cover, preferably made of fine knit jersey cloth with the threads running horizontally so as to make the fabric most stretchable in a transverse direction. This cover is cut to the same general shape and dimensions as the lining 10, but slightly longer than the latter so as to overlap it slightly at both the upper and lower edges, and it is detachably secured to the lining by means of snap-fastener members 26, 27 placed at the front and back of the upper edges and along the vertical front edges of the garment, the fastener members 26 on the lining being located on the fabric bindings thereof. The width of the cover 25 is substantially the same as that of the lining 10 at the top edge of the garment, but in the lower portion the cover is made of a normal width somewhat greater than that of the lining, so that when the garment is unstretched the cover will have a fullness in its lower or hip-covering portion and will fit smoothly when the garment is stretched as indicated in the drawings.

The fabric cover 25 absorbs the perspiration which passes through the small holes in the rubber lining, confers a neat outward appearance, and prevents the chafing of the adjacent outer clothing against the rubber. By detachably supporting said cover on the lining in the manner set forth, we make a unit of the two for convenience of handling but allow the disconnection of the two and their effective separate cleansing, as well as the renewal of either member independently.

of the other when damaged from wear or other cause.

It will be manifest that our invention may be embodied in various forms of reducing 6 garments, and the details of construction may be suitably modified within the scope of our claims.

We claim:

1. A body girdle comprising an elastic, 10 non-absorbent rubber lining having numerous small openings therethrough to permit the escape of perspiration, a fabric cover loosely overlying said lining for absorbing the perspiration, and separable fasteners 15 connecting the edge portions of said lining and cover and permitting complete detachment of the cover, thus allowing the lining and cover each to be completely cleansed independently of the other.

2. A body girdle according to claim 1 in 20 which the lining is made of perforated sheet rubber having smooth and readily cleansable surfaces on both sides.

3. An abdominal girdle according to claim 1 in which the lower edge of the cover, 25 between its ends, is free from the lining and it and the adjacent lower portions of the cover are of greater width than the lining when the latter is unstretched, permitting the lining to be stretched over the wearer's 30 hips and thereby to tighten said lower portions of the cover.

In witness whereof we have hereunto set our hands, said BERTRAM G. WORK this 27th day of August, 1924, and said LOUISA N. 35 SLADE this 8th day of September, 1924.

BERTRAM G. WORK.
LOUISA N. SLADE.
